Robert W. Walton

BY
Bob W. Kitchel
ATTORNEY.

UNITED STATES PATENT OFFICE.

ROBERT W. WALTON, OF PHILADELPHIA, PENNSYLVANIA.

CIRCULAR-KNITTING MACHINE.

Application filed September 17, 1921. Serial No. 501,316.

To all whom it may concern:

Be it known that I, ROBERT W. WALTON, a citizen of the United States, residing at Philadelphia, county of Philadelphia, and 5 State of Pennsylvania, have invented a new and useful Improvement in Circular-Knitting Machines, of which the following is a full, clear, and exact description, reference being had to the accompanying drawings, 10 which form a part of this specification.

My invention relates to circular knitting machines, more especially those knitting continuous tubular fabric in the manufacture of hosiery. This tubular fabric is afterwards cut into lengths, upon which foot portions are knitted, and it is common practice to knit what is termed a loose course near the end of each of said lengths for the following reason.

20 After being cut into lengths, as described, each piece is mounted by hand on a transfer ring. This ring comprises a circle of points equal in number to the needles in the circular knitting head and one end of each piece 25 is pressed onto this ring so that one of the points projects through each individual loop in one of the courses of the tubular fabric near the end of the piece. This is called the topping operation. The ring is then inverted over the knitting head of a machine 30 for knitting the foot portion and the loops are transferred from the points to the needles of the machine whereby everything is in readiness for the operation of knitting 35 the foot onto the length of tubular fabric.

Therefore, after a certain length of regular tubular fabric has been knitted, the machine is set to automatically knit a course of elongated stitches wherein the yarn is pulled out to a greater length by the needles 40 for the purpose of facilitating the topping operation. However, it is found in practice that the knitting of this loose course is very apt to produce drop stitches, necessitating 45 a mending operation before the piece is ready for topping, adding appreciably to the time and cost of production. It is to obviate this difficulty that my invention is designed.

50 It is customary to knit the stocking fabric with two threads of yarn. In the process of knitting, one of these threads is bound to be in greater tension than the other, with

the result that in the loose course the tighter thread stays on the needles and forms all 55 the loops of the course, but the looser thread is frequently thrown off and drops many stitches which, if not caught in again and mended, would debar them from being caught on the transfer points and form a 60 weak and imperfect stocking at that point.

In order to draw out more yarn and form the loose course, the main stitch cam of the machine is lowered to depress the cylinder needles below their regular knitting depth 65 and at the same point a cam is introduced beneath the dial needles for raising them up, thus lengthening the distance between the heads of both sets of needles just at the point where the yarn is fed in and therefore 70 drawing longer loops.

Drawing the longer loops tends to pull up on the cylinder needles with the result that directly their butts have passed the lowest point of the depressed knitting cam, they 75 are at once raised up to the guard cam. This immediate raising of the cylinder needles, together with the lowering of the dial needles to their regular level directly they have passed the cam at the knitting point, produces such a slack in the fabric between the 80 needles that many stitches are dropped.

In my invention I provide means for lowering the guard cam just following the lowering of the main stitch cam with the 85 result that when the cylinder needles pass the lowest point of the stitch cam they are not allowed to be drawn up as heretofore, but their butts, striking this lower guard cam, 90 are deflected gradually to their normal level, and the loops on the needles are not allowed to become so slack as to fly off and form drop stitches.

Having now described in general terms the object of my invention, the necessity for 95 and value of which will be readily understood and appreciated by those skilled in the art, I will proceed with a detailed description of mechanism employed in lowering the guard cam as described in connection with 100 the accompanying drawings, in which,—

Fig. 1 is a diagrammatic showing of a section of fabric showing a loose course.

Fig. 1^A is a similar view showing dropped 105 stitches.

Fig. 2 is a cross-section through one side

of the knitting head of the machine, showing the dial and circular needles at the knitting point.

Fig. 3 is a plan view of a portion of the 5 cam ring embodying my invention.

Fig. 4 is a developed front view of the mechanism shown in Fig. 3.

Fig. 5 is a rear or outside view of the mechanism shown in Fig. 3.

10 The cylinder stitch cam *a* is secured to post *b* which is vertically slidable through the top *c* of the cam ring, and normally pressed upward by a spring not shown, as is old and well known in the art. Post *b* carries a head *d*, in the form of a cam plate, which is adapted to be actuated by set screws *e* in an arm *f* secured to a pivot post *g* mounted in the cam ring. An adjusting screw *t*, which overhangs the edge of plate *d*, limits the upward movement of the knitting cam. A clamp *h* is mounted on the set screws and carries a cam *i* for acting on the dial needles *j*. Pivot post *g* carries an arm *k* which projects beyond the cam ring 20 and is actuatable by well known means to turn the pivot post and with it arm *f*.

I have mounted the guard cam *m* on a post *n*, vertically slidable through top *c* of the cam ring and normally held up by spring 30 *o* so the cam is against under side of top *c*, as indicated in broken lines in Fig. 4. For depressing the guard cam, I provide a two-piece block *p* clamped to set screws *q* screwed into arm *f* in such a position that a beveled 35 portion *r* of the block will act upon the similarly beveled top of post *n*, in the inward turning of arm *f*, to depress said post. By loosening the clamp of block *p* and screwing set screws *q*, the block may be adjusted to 40 give post *n* and guard cam *m* the downward movement required.

Normally arm *f* is turned outwardly so its set screws *e* are out of action with regard to cam plate *d*. When a loose course is to be 45 knit, as hereinbefore described, arm *k* is actuated to turn arm *f* inwardly until set screws *e* contact with and override plate *d*, pressing it downward and with it the knitting cam *a* to lower the cylinder needles *s*. 50 At the same time cam *i* acts to raise the dial needles *j* and lengthen the pull of the yarn between the two sets of needles. While the knitting cam *a* is being depressed by set screws *e* moving on the cam face of plate *d*, 55 the beveled corner *r* of block *p* contacts with post *n* and starts to depress it and with it the guard cam *m*. When arm *f* completes its inward turn, both cams *a* and *m* arrive at their lower position and remain so until 60 the loose course is completed when arm *f* is withdrawn and they again rise to their normal knitting position.

This method of action, whereby the stitch cam leads in the downward movement and is 65 followed by the guard cam, is necessary in

order not to put an extra strain on the loops formed just before the cam was lowered, which would be stretched and broken if the two cams acted simultaneously.

In the knitted fabric indicated in the diagrams, Figs 1 and 1^A the two strands of yarn should always act together as if they were a single thread. A perfect loop in the loose course is thus indicated at *x*, and *y* indicates drop stitches of one of the strands, the 70 tighter thread being held on the needles and knitted, as previously described. It will be understood that when knitting with a single strand, the thread is liable to be thrown off the needles on the loose course in a similar 75 manner, so that my invention applies equally for use in knitting with single or double threads.

The advantages of my invention result from the provision of means for maintaining the cylinder needles depressed for a short distance beyond the low point of the stitch cam for the circular needles and thereby maintain the newly formed loops under tension, which will prevent the dropping of 80 stitches. By maintaining the cylinder needles depressed for a short time after the loops have been formed, I am not only enabled to form a loose course without danger of dropping stitches, but am enabled to form 85 a very much looser course than heretofore, which is very desirable to facilitate transferring, and at the same time I am enabled to make a loose course having very long 90 stitches without lowering the stitch cam a great extent. This I am enabled to do as the needles, as they pass under the stitch cam, draw the yarn from the yarn supply only and not from the yarn supply and the newly 95 formed loops on the needles, which have just 100 passed under the stitch cam.

By depressing the guard cam a short time after depressing the stitch cam, I avoid all danger of straining the short loops formed on the cylinder needles just prior to the 105 lowering of the stitch cam.

The two cams are arranged to reach their lowest position and act upon the needles at substantially the same relative time—relative as regards the needles. That is, by the 110 time the first needles passing under the lowered stitch cam reach the guard cam, it also is in lowered position, then and not till then.

The lag of the guard cam is equivalent to the time it takes the needles to pass from the low point of one cam to the low point of the other. This allows the needles to be thrown off, and does not unduly strain the last preceding short loops as the guard cam curves off from this point allowing the needles to rise, and also those last few short loops draw some thread from the first long ones.

Similarly, at the end of the loose course, 125 the stitch cam leads in the rising movement 130

by just the time it takes the last long loop needle to reach the low point of the guard cam. Then and not till then does the guard cam rise, which serves to keep sufficient tension on the last long loop to prevent its being thrown off and yet does not unduly stretch the first short loops for the same reasons given in the other case.

Having now fully described my invention, 10 what I claim and desire to protect by Letters Patent is:

1. In a circular knitting machine, in combination, cylinder needles and dial needles, a knitting cam and a guard cam for the cylinder needles, loose course cams for both cylinder and dial needles, a shift cam for depressing the guard cam, and means for actuating the loose course and shift cams, said means being arranged to cause the shift 20 cam to operate directly after the operation of the loose course cams.

2. In a circular knitting machine, the combination of cylinder and dial needles and means for depressing the former and raising 25 the latter to form a loose course, of shiftable means actuated by said former means, to restrict the return movement of the cylinder needles after their depressing means has acted, whereby drop stitches are prevented.

3. A circular knitting machine comprising needles, a stitch cam and a guard cam, means to depress the stitch cam to cause the needles to draw longer loops, and means to 30 depress the guard cam to prevent the needles rising too high after the first named means has acted, whereby said loops are maintained

taut enough to prevent their being thrown off to form drop stitches.

4. In a circular knitting machine, dial needles and cylinder needles, a stitch cam 40 and a guard cam for the cylinder needles, means for producing a loose course comprising a cam for depressing the stitch cam, an arm for actuating said depressing cam, a cam mounted on said arm for raising the 45 dial needles, another cam on said arm for depressing the guard cam, adjusting means therefor, and means for again raising the guard cam.

5. A cam cylinder for knitting machines 50 having a stitch cam, a guard cam, and means for first shifting the stitch cam to lengthen the stitch and then similarly shifting the guard cam, while knitting, sufficiently to prevent the too sudden shortening of the 55 stitch.

6. A cam cylinder for knitting machines having a stitch cam, a guard cam, and a lever for lowering the stitch cam a certain distance and then lowering the guard cam a 60 less distance.

7. In a circular knitting machine, means for knitting a loose course comprising a movable stitch cam and an arm for depressing said stitch cam, a movable guard cam, 65 and a cam on said arm for depressing the guard cam when the stitch cam is depressed.

In testimony of which invention, I have hereunto set my hand, at Philadelphia, Pa., on this 14th day of September, 1921.

ROBERT W. WALTON.
